POWER LINE SUPPORT OR THE LIKE

Everett W. Chaille, Fairborn, Ohio

Application January 8, 1959, Serial No. 54,081

Term of patent 14 years

(Cl. D26—9)

Figure 1 is a perspective view of my power line support or the like;

Figure 2 is a top plan view;

Figure 3 is a left side elevational view;

Figure 4 is a cross-section along line 4—4;

Figure 5 is a cross-section along line 5—5 thereof; and

Figure 6 is a cross-section along line 6—6.

I claim:

The ornamental design for a power line support or the like, as shown.
